Marie Joseph Victor Pierre de Montesquiou
Fezensac, Neuilly-S/Seine, France

Application January 11, 1951, Serial No. 13,757

Term of patent 7 years

(Cl. D58—8)

To all whom it may concern:

Be it known that I, Marie Joseph Victor Pierre de Montesquiou Fezensac, a citizen of the Republic of France, residing at Neuilly-S/Seine, in the city of Seine and Republic of France, have invented a new, original, and ornamental Design for a Bottle, of which the following is a specification, reference being had to the accompanying drawing, forming part thereof.

In the drawing

Fig. 1 is a front elevational view of a bottle, showing my new design;

Fig. 2 is a rear elevational view thereof;

Fig. 3 is a side elevational view thereof;

Fig. 4 is a central vertical section taken along lines 4—4 of Fig. 1; and

Fig. 5 is a top plan view thereof.

I claim:

The ornamental design for a bottle, substantially as shown.

MARIE JOSEPH VICTOR PIERRE
DE MONTESQUIOU FEZENSAC.
